UNITED STATES PATENT OFFICE.

SINAI LAFLEUR, OF FOLEYET, ONTARIO, CANADA, ASSIGNOR OF ONE-THIRD TO J. EDOUARD CORON, OF MONTREAL, QUEBEC, CANADA.

AUTOMATIC TRAIN-STOP.

1,378,800.

Specification of Letters Patent.

Patented May 17, 1921.

Application filed November 19, 1920. Serial No. 425,187.

To all whom it may concern:

Be it known that I, SINAI LAFLEUR, a subject of the King of Great Britain, and resident of the town of Foleyet, in the Province 5 of Ontario, Dominion of Canada, have invented certain new and useful Improvements in Automatic Train-Stops, of which the following is a specification.

This invention relates to improvements in 10 automatic train stop device, and the objects of the invention are to provide simple and effective means by which trains may be stopped whenever any of the trucks supporting the car body become displaced or 15 by which accidents of a serious nature may be avoided; further objects are to provide an invention of this character of simple construction, composed of few and simple parts, all well designed to perform the work 20 required of them, and it consists essentially of the improved construction hereinafter described in detail in the accompanying specification and drawings.

In the drawings:

25 Figure 1 is a side elevation of the freight car having my invention applied thereto. Fig. 2 is a plan view of the underside of the car with the car body indicated in dotted lines. 30 Fig. 3 is a perspective view of the working parts of the device. Fig. 4 is a perspective detail of the trip device.

35 In the drawings like characters of reference indicate corresponding parts in all the figures.

Referring to the drawings:

A indicates a freight car, and B the trucks thereof, of which two are shown; C indicates the train line pipe, D the triple valve, and E, the compressed air reservoir, all of 40 well-known construction; F indicates a release valve or angle cock of any convenient design having a controlling lever 10, designed when in the position indicated in dotted lines, to open the valve F, and thus open the train line pipe and apply the air brakes. The valve F is connected to the train line pipe and to the triple valve by 45 any convenient means.

50 A T-connection 11 connects with the pipe 12 leading from the T-connection 13 on the train line pipe, the said T valve 11 connecting on the side with a pipe 14 which extends 55 to the triple valve.

The lever 10 is normally retained in closed position by means of a rod or link 15, extending to a ring 16, which is supported on an open hook 17 carried by a bracket 18.

When the ring 16 is disengaged from the hook, the lever 10 under actuation of a spring 19, is designed to move the valve F to open position, the opposite end of the spring 19 to that connected to the lever 10 being supported by an arm 20 formed on 60 a bracket 21, both the brackets 18 and 21 being connected to the underside of the car body.

Means are provided, according to the present invention, whereby displacement of the 70 trucks, or, in fact any other desired part of the car body, should disengage the ring 16 from the hook 17, and thus cause application of the brakes.

The means I have shown comprising a 75 plurality of cables, wires or cords 22 each connected to the ring 16 and extending over suitably placed pulleys 23 to the trucks.

In the embodiment I have illustrated, the 80 cables 22 extend through perforations 24 formed in extension plates 25 on the ends of the truck, the cables having rings 26 at their extremity which will serve to retain them in position and which will also serve as a means of applying the brakes in the 85 case of emergency, or, in the case of a runaway car.

It will be seen that any person adjacent to the car while it is passing at a moderate speed can seize one of the rings 26 and pull 90 the cable 24, thus disengaging the ring 16 and permitting the lever 10 to swing under the spring 19 and thus apply the air brakes, as already explained.

As many changes could be made in the 95 above construction, and many apparently widely different embodiments of my invention, within the scope of the claims, constructed without departing from the spirit or scope thereof, it is intended that all matter 100 contained in the accompanying specification and drawings shall be interpreted as illustrative and not in a limiting sense.

What I claim as my invention is:

1. An automatic train stop comprising a 105 valve operatively connected to the air brake system, adapted when opened to permit the escape of air and cause the application of the brakes, spring means tending to move the valve to open position, a trip device nor- 110

- 5 mally retaining the valve in closed position, releasing means for the trip device including cables extending to different parts of the car construction, and pulleys supporting the cables.
- 10 2. An automatic train stop comprising a valve operatively connected to the air brake system, adapted when opened to permit the escape of air and cause the application of the brakes, spring means tending to move the valve to open position, a trip device normally retaining the valve in closed position, and releasing means for the trip device operable by displacement of certain parts of 15 car construction said releasing means being also manually operable.
- 15 3. An automatic train stop comprising a valve operatively connected to the air brake system, adapted when opened to permit the escape of air and cause the application of the brakes, spring means tending to move the valve to open position, a trip device normally retaining the valve in closed position, and car trucks having perforated extension 20 plates, and releasing means for the trip device including cables extending through the extension plates and having rings at their extremity, and pulleys supporting the cables.
- 25 4. An automatic train stop comprising an air release valve connected to the air brake system, and lever controlling the same, spring means normally tending to move the lever to open position of the valve, a link connected to the lever, a ring on the link, a hook member supporting the ring and normally retaining the same, means for disengaging the ring from the hook, adapted to be operated by displacement of certain parts of the car construction. 35
5. An automatic train stop comprising an air release valve connected to the air brake system, and lever controlling the same, spring means normally tending to move the lever to open position of the valve, a link connected to the lever, a ring on the link, a hook member supporting the ring and normally retaining the same, means for disengaging the ring from the hook, adapted to be operated by displacement of certain parts of the car construction, the said means including cables, and pulleys supporting the cables. 40
- 50 In witness whereof I have hereunto set my hand in the presence of two witnesses.

SINAI LAFLEUR.
